[57] CLAIM

The ornamental design for a magnetic disk drive for game machine, as shown and described.

DESCRIPTION

FIG. 1 is a front elevational view of a magnetic disk drive for game machine showing a first embodiment;

FIG. 2 is a top plan view thereof;

FIG. 3 is a rear elevational view thereof;

FIG. 4 is a bottom plan view thereof;

FIG. 5 is a right side view thereof, the left side view being identical thereto;

FIG. 6 is a top, front, and right side perspective view thereof;

FIG. 7 is a bottom, rear, and left side perspective view thereof;

FIG. 8 is a front elevational view of a magnetic disk drive for game machine showing a second embodiment;

FIG. 9 is a top plan view thereof;

FIG. 10 is a rear elevational view thereof;

FIG. 11 is a bottom plan view thereof;

FIG. 12 is a right side view thereof, the left side view being identical thereto;

FIG. 13 is a top, front, and right side perspective view thereof; and,

FIG. 14 is a bottom, rear, and left side perspective view thereof.
